CLAIM

The ornamental design for an autonomous transport robot, as shown and described.

DESCRIPTION

Figure 1.1 is a front view of an autonomous transport robot;

Figure 1.2 is a left side view thereof;

Figure 1.3 is a rear view thereof;

Figure 1.4 is a right side view thereof; and

Figure 1.5 is a top view thereof.

The bottom view is flat and includes no surface ornamentation, and thus the bottom view has been omitted.
